UNITED STATES PATENT OFFICE

2,505,096

VEGETABLE CHOPPER AND DICER

Claude J. Christopher, Los Angeles, Calif.

Application December 13, 1946, Serial No. 716,073

1 Claim. (Cl. 30—303)

1

My present invention relates to an improved vegetable chopper or dicer of the type using a plurality of razor blades conventionally known as safety razor blades and consisting in an unique combination and arrangement of parts for securing the blades in working position, and for permitting the removal of the blades for cleaning or replacement.

In the accompanying drawings I have illustrated one complete example of the physical embodiment of my invention according to the best mode I have thus far devised, but it will be understood that various changes and alterations may be made in the exemplified structure within the scope of the appended claim.

In the drawings:

Figure 1 is a side elevational view partially broken away to show the interior.

Figure 2 is a vertical sectional view.

Figure 3 is a horizontal sectional view at line 3—3 of Figure 2.

Figure 4 is a plan view of the slotted blade receiver, and Figure 5 is an end view thereof.

Figure 6 is a sectional view at line 6—6 of Fig. 4.

Figure 7 is a vertical sectional view at line 7—7 of Fig. 3.

Referring now to the drawings I provide a disk or plate 2 having radial slots 4 into which are inserted razor blades 6 having backs 8. A securing nut 10 is centrally located on the disk and peripheral notches 12 are formed to align the cover 14 having peripheral notches 16 and pressed ribs 18 radially aligned with the slots of plate 2 and formed to secure the backs of the blades.

A central aperture 20 has a flange 22 resting on the nut 10, and the handle 24 is formed with a threaded stud 26 which is passed through the aperture and engages the nut. The parts are thus secured in position.

2

The blades are held vertically in the slots and the device may be assembled and dismantled with facility and ease for cleaning or replacement of a broken or damaged blade. For storage the blades may be removed from the slots and placed horizontally in the space between the plate and the cover as defined by the height of the nut.

Having thus fully described my invention what I claim as new and desire to secure by Letters Patent is:

A food dicer or chopper comprising a radially slotted plate, a securing nut fixed to the center of said plate, a plurality of relatively spaced notches in the periphery of said plate a plurality of razor blades in the slots, a cover having depressed ribs aligned with and securing the upper ends of the blades, a depending annular flange on said cover, relatively spaced notches in the flange adapted to engage the notches in the plate to prevent relative movement of the plate and cover with regard to each other, a centrally located aperture in said cover, a depressed flange surrounding said opening on the plate engaging the flange on the cover for the spacing of the plate and cover, and a handle having a stud through the central aperture in the cover and engaging the nut to firmly retain the plate and cover in fixed relation to each other.

CLAUDE J. CHRISTOPHER.
